(57) **CLAIM**

The ornamental design for a chair arm, as shown and described.

DESCRIPTION

FIG. 1 is a perspective view of a chair arm;
 FIG. 2 is a front elevational view of the chair arm;
 FIG. 3 is a first side elevational view of the chair arm;
 FIG. 4 is a rear side elevational view of the chair arm;
 FIG. 5 is a second side elevational view of the chair arm;
 FIG. 6 is a top plan view of the chair arm; and,
 FIG. 7 is a bottom plan view of the chair arm.
 The broken lines in the drawings form no part of the claimed design.

1 Claim, 4 Drawing Sheets# US D888,479 S
